22 INVENTOR,
Richard L. Bache
BY
Henry J. Bache,
HIS ATTORNEY

UNITED STATES PATENT OFFICE

RICHARD L. BACHE, OF WOODHAVEN, NEW YORK

LOCK

Application filed November 22, 1928. Serial No. 321,106.

This invention relates to improvements in locks.

My invention is particularly adapted for door locks of automobiles.

5 A primal feature of my invention is the mounting of the knob of the lock to actuate the latch bolt from its closed to its open position by pressure on the knob in the direction of the desired movement of the door. That 10 is to say, when the occupant of the automobile desires to exit from the automobile, the inner handle of the lock is pushed in the outward direction of the swing of the door, to thereby move the latch bolt from closed to open position; and correspondingly when it is desired 15 to enter the automobile the outer handle of the door is pulled, i. e., in the direction of outward swing of the door.

Pursuant to such objects a preferred form 20 of my invention comprises a case, a latch bolt movable in the case, a spindle for the handle mounted for axial displacement, handle parts for the opposite sides of the door secured to the spindle and members associated with 25 the latch bolt at the handle spindle for automatically holding the latch bolt in its closed position and for moving the latch bolt from closed to open position upon axial displacement of the handle parts in the direction of 30 the desired opening of the door.

Further features and objects of my invention are more fully described in the accompanying drawings, in which

Fig. 1 is a detail horizontal cross section 35 of an automobile door and associated body parts provided with a latch or lock embodying my invention; Fig. 2 is a sectional elevation on line 2—2 of Fig. 1; Fig. 3 is a front elevation of the same; and Fig. 4 is a sectional elevation on line 4—4 of Fig. 2, and Fig. 5 is a detail elevation of the inner handle.

Referring to the drawings, the door of the automobile is shown in outer view in Fig. 3; the front face of the door is indicated by 10. 45 The lock proper comprises a casing 11 which is suitably positioned between the door front 10 and the rear 12 of the door. The casing may conveniently include a face plate 13 extending the full thickness of the face of the door, and having an opening 14 through

which the bolt 15 of the latch emerges. The striker plate 16 coacts with the latch to hold the door closed. For automobile use, an initial holding recess 16a and a full closure recess 16b are preferably provided.

55 The essentials of the lock proper include a spindle 17 having at its front end a suitable form of handle 18 which may be secured in position to the front end of the spindle by means of a positioning screw. The inner end 17b of the spindle 17 preferably extends through the inner side of the door and the inner handle 19 is secured thereto by its positioning screw 20.

60 Suitable escutcheon plates 21, 22 may be employed for ornamentally concealing the outer and inner openings through the door through which the outer and inner handle parts of the spindle project.

To attain the desired automatic closing of 65 the door latch bolt and the movement of the latch bolt from closed to open position by displacement of the handle and its spindle axially in the direction of outward swing of 70 the door, I provide a member 23 controlling 75 the latch bolt having an inclined face 24 cooperating with an inclined face 25 controlled by the spindle of the handle.

The member 23 may be in the form of a block initially secured by a screw, clamp or 80 the like to the shank 26 of the latch bolt, or may be cast integrally therewith.

Suitable means is provided for holding the bolt 15 in its closed position; such holding means is preferably resilient as in the form of 85 a pair of expansive springs 27 having its one end 27a lodged about a lug 28 on the inner face of the casing 11 and its opposite end 27b lodged about a lug 29 on the shank 26 or member 23.

90 Suitable means is also provided for guiding or maintaining the shank 26 in its reciprocatory movement to and from its closed position; such means is most simple and effective in the form of an expansive spring 30 having 95 its one end 30a lodged about a lug 31 on the member 23 and its opposite end 30b lodged about a lug 32 on the casing 11.

Preferably, the shank 26 of the spindle is 100 in the form of a plate which is centrally

slotted as indicated at 26a, see Figs. 2 and 4, to receive and retain the handle spindle 17.

It will be observed that when the passenger desires to enter the automobile, he grasps the outer handle part 18 and pulls the same in the direction of the arrow 33, see Fig. 1, whereby the spindle 17 is actuated in the direction of the arrow 34, i. e., axially of the spindle 17 and thereby forcing the inclined face 25 of the enlargement of the spindle 17 into contact with the inclined face 24 of the member 23 controlling the shank 26 of the latch bolt 15, and whereby the shank 26 and the latch bolt 15 are moved in the direction of the arrow 35, see Fig. 1, counter to the springs 27 and compressing the same, until the latch bolt 15 has wholly emerged from a closure recess of the striker plate 16, whereupon the door swings outwardly on its hinges in the direction of the arrow 33.

Similarly, when the passenger desires to leave the automobile, the inner handle 19 is pushed in the direction of the arrow 34, Fig. 1, and corresponding action of the lock parts takes place.

My invention is also advantageous in the stage of closing the door, in that by grasping the handle, either by pulling its outer handle 18 or by pushing the inner handle 19, in both instances the flat face 25a is brought into engagement with the contiguous portion of the inner flat face 11a of the casing 11, thereby wholly freeing the stay bolt 15, its shank 26 and its controlling member 23 from engagement with the handle parts, and particularly the spindle 17, and rendering the manual force applied to the door wholly effective in moving the door to its closed position.

A key-lock 36 may be provided for locking the lock proper in its closed position; such key-lock 36 is preferably accessible from the exterior side of the door. The key-lock 36 may effect locking by engagement of its bolt 37 in the recess 38 of the spindle 17.

Preferably, as appears in Figs. 1, 4 and 5, the inner handle 19 is arranged as a plate flush with or countersunk relative to the inner face 12 of the door, so that the door may not be accidentally struck or engaged by the body of a passenger within the automobile. For such purpose, the inner escutcheon plate 22 is provided with an oval or other suitable opening 22a, having a correspondingly curved flange 22b, for guiding the inner push plate 19.

The contour of the inner push plate 19 may be designed to accommodate receiving the thumb or two fingers for applying pressure for opening the door from the interior of the automobile body.

While my invention is particularly adaptable for locks of automobile doors, it will be apparent that the invention is applicable for general use in doors.

Whereas I have described my invention by reference to specific forms thereof, it will be

understood that many changes and modifications may be made without departing from the spirit of the invention.

I claim:—

1. The combination of a door for an enclosure, means for mounting said door to open in a direction outwardly of said enclosure, said door being provided with recesses respectively on its inner and outer faces, a latch bolt carried by said door, means having an inclined face controlling said latch bolt, spring means biasing said latch bolt toward its locking position, a handle for the outer face of the door constructed to be pulled manually, a member adapted to be pushed manually at the inner face of the door and wholly disposed within said recess on the inner face of said door, a spindle unitarily connecting at its outer end said handle through said recess on the outer face of the door and said push member at its inner end, and means operated by said spindle for operating said inclined faced means, whereby said latch bolt is moved to open position against its said spring biasing means by manually pulling said handle on the exterior of the door and by manually pushing said push member on the interior of the door.

2. The combination of a door for an enclosure, means for mounting said door to open in a direction outwardly of said enclosure, said door being provided with recesses respectively on its inner and outer faces, a latch bolt carried by said door, means having an inclined face controlling said latch bolt, spring means biasing said latch bolt toward its locking position, a handle for the outer face of the door constructed to be pulled manually, a member adapted to be pushed manually at the inner face of the door and wholly disposed within said recess on the inner face of said door, a spindle unitarily connecting at its outer end said handle through said recess on the outer face of the door and said push member at its inner end, and inclined means operated by said spindle for operating said inclined faced means, whereby said latch bolt is moved to open position against its said spring biasing means by manually pulling said handle on the exterior of the door and by manually pushing said push member on the interior of the door.

In testimony whereof I have signed this specification this 21st day of Nov., 1928.

RICHARD L. BACHE.
